AUTOMATIC BRAKING MECHANISM

Application filed September 5, 1929. Serial No. 390,482.

This invention relates to braking mechanism and more particularly to automatic braking mechanism for elevators.

Heretofore elevators have been equipped with braking mechanism operable upon excessive speed of the car to stop the same. The mechanism in some instances comprises a pair of jaws adapted to grip the guide rail of the elevator when they are forced into contact therewith by means of a wedge member operated as the result of rotation of a drum by a speed governed cable. Such a mechanism is satisfactory to some degree for stopping an elevator when the same is fully loaded since the weight or momentum of the elevator causes the jaws to slide along the guide rail before firmly gripping the same. However, when the car is loaded otherwise than full load, the action of the jaws upon excessive speed of the elevator is to stop the same so suddenly as to endanger occupants of the car. This is due to the fact that the weight in the car causes its momentum to be decreased an amount sufficient to permit the jaws to lock along the guide rail and stop the car too suddenly.

An object of the present invention is to provide improved braking mechanism for automatic operation upon excessive speed of an elevator.

Another object of the invention is to provide braking mechanism for elevators with devices for compensating for variation in load of the elevator.

In accordance with the present invention, use is made of a pair of jaws sliding along one of the guide rails which jaws are forced into contact with the rail by means of the usual wedge. However, instead of making the closing of the jaws positive due to the wedge, one of the jaws is so arranged as to permit it to slide along the rail without actually locking thereagainst. A tension device is interposed between parts of this slit jaw so that the tension exerted by the wedge may be relieved when the momentum of the elevator is less than the predetermined minimum required for locking the jaws within the specified distance along the guide rail. Sometimes it is desirable to place the safety mechanism

on the counterweight frame, thereby precluding excess speed of the elevator in an upward direction.

Other objects and features of the invention will become evident by consideration of the following detailed description taken in connection with the accompanying drawings wherein

Fig. 1 is a side elevation of the mechanism employed in the present invention.

Fig. 2 is a section taken on the lines 2—2 of Fig. 1, and

Fig. 3 is a section taken on the lines 3—3 of Fig. 1.

Referring now to the drawings, 10 indicates the frame members comprising the sling of the elevator car which sling is slidable along the usual guide rails 11, one of which is illustrated herein. As is usual in elevator constructions, a cable 12 is so mounted as to move concurrently with the car, its movement being between a pair of cam-like rollers 13 which are governed by automatic governing mechanism not illustrated herein and forming no part of the present invention. Secured to cable 12 in any desired manner is a cable 14 passing around idler rollers 15 affixed to the elevator car proper and wound upon a drum 16 mounted beneath the sling of the car. Drum 16 is rigidly secured to a collar 17 which collar is mounted for rotation in bearing members 18, one of which is illustrated herein. The collar 17 is internally threaded for the reception of a rod 19 one end of which is formed in the shape of a wedge 20.

Mounted beneath the sling of the car for pivotal movement is a member 21 having a jaw 22 adapted to engage one side of the guide rail 11 and at the other end a wedge follower 23 contacting with wedge 20. Oppositely located for pivotal movement is a second member 24 having a jaw 25 engaging the opposite side of rail 11 but having at its free end a fork 26 so shaped as to permit the mounting therein of a threaded bar 27. The pivotal portion of member 24 is in substantial L-shape upon shaft 28 and pivotally mounted on this shaft between the parts comprising the L-shaped portion is a member 29 having a wedge follower 30 at the free end thereof.

Rigidly secured to the threaded bar 27 in any desired manner is an arm 31 having adjustably secured thereto a weight 32. This arm 31 is normally held in a desired position through the agency of a spring 33. The arm 31 is connected by a link 34 with a head 38 on the end of a rod 36 around which the spring 33 is positioned. This rod 36 as shown passes through a flange 37 secured to the channel bar 10 which forms a part of the saddle of the car. The tension of the spring 33 may be adjusted by manipulation of nuts 35 threaded on the end of rod 36 and working against a washer 39 which is directly in contact with one end of the spring, the other end of which rests against the top of flange 37.

As will be seen clearly in Fig. 2, one end of threaded rod 27 rests against the member 29 so that movement of this member due to movement of the wedge will be transmitted to the member 24 which has as a part thereof the jaw 25.

The operation of the braking mechanisms is substantially as follows. Let it be assumed that the car is fully loaded for which condition the spring 33 is so adjusted and the weight 32 so positioned that stopping of the car within the selected distance will have no effect thereon. Under these conditions let it be further assumed that the elevator exceeds its maximum speed. The governing mechanism (not shown) will cause the cam rollers 13 to be moved, gripping the cable 12 which moves concurrently with the car. This gripping motion arrests movement of cable 12 and as a result continued movement of the car causes the unwinding of cable 14 from drum 16 thereby rotating this drum. Rotation of the drum 16 causes the wedge 20 to be moved in a direction away from the guide rail 11 forcing the wedge followers 23 and 30 outwardly. This movement of the wedge followers is transmitted in one instance directly to jaw 22 and in the other instance through the rod 27 to jaw 25. The weight of the car and the momentum thereof under full load will cause the jaws 22 and 25 to slide along the rail a short distance until further rotation of drum 16 causes them through the agency of wedge 20 to be firmly locked against the rail. Under these normal conditions the locking of the jaws will take place within the selected distance approved by safety factors. In the operation just described, the arm 31 is inactive due to tension on spring 33 thereby holding rod 27 against rotation and permitting the jaw 25 to be locked without interference.

Let it now be assumed that the car is very lightly loaded. When it exceeds its maximum speed the cable 12 as before is locked against movement, unwinding cable 14 and rotating drum 16. This movement of drum 16 holds the wedge 20 between the followers 23 and 30 and forces jaws 22 and 25

against the guide rail. Since the weight of the car is reduced and consequently the momentum thereof is less, the normal tendency would be for the jaws to lock quickly against the rail, stopping the car almost immediately. However, when the car starts its rapid stopping the weight 32 swings the arm 31 downwardly causing a slight rotation of bar 27, moving it a fractional distance from member 29 and thereby relieving tension on the jaw 25. Continued movement of wedge 20 tightens the member 29 against the end of the rod 27 again applying pressure to force jaw 25 against the rail 11. If this stopping is still too suddenly applied, the weight 32 due to its momentum will further release rod 27 easing up on the gripping of jaw 25. As soon as the stopping of the car has reached normal operation, the spring 33 will prevent further movement of arm 31 and accordingly the two jaws will be locked against the rail.

It is to be understood that the apparatus will function by causing each jaw to be yieldable as well as by causing one as illustrated. If so desired separate weights may be utilized in connection with each jaw for securing this yieldable gripping or a single weight may be utilized for both jaws. Or there may be a pair of jaws on each side of the elevator with lever connections from each of said pairs operating with a common weight. It should be borne in mind, for the purposes of this invention, that it makes no difference whether the inertia weight is connected to one of a pair of jaws or both jaws of a pair, or whether it is connected to more than one pair of such jaws, as such changes would all come under the heading of slightly different embodiments of this invention appropriate to anyone skilled in such work.

From the foregoing it will be seen that the present invention provides mechanism whereby an elevator will be automatically stopped within a selected distance under any condition of load thereof. It will be understood of course that the weight 32 will be of such size and so positioned on arm 31 and the tension of spring 33 will be so adjusted that under normal load conditions the jaws will be locked without interference or without easing up on pressure by rotation of rod 27. Whenever the car is lightly loaded and is stopped too suddenly the momentum transmitted to weight 32 is sufficient to depress arm 31, easing the tension on one of the jaws and thereby permitting the stopping of the car to be gradual instead of abrupt.

It will be seen that the present invention provides mechanism whereby the factor of safety in stopping cars automatically under emergency conditions is observed for any type loaded car so that the stopping of the car in any instance will be gradual and dis-

tributed over the selected distance along the guide rail. It is to be understood that the invention is not to be limited to the illustrated embodiment but is to be limited only by the scope of the following claims.

5 I claim:

1. Apparatus of the character described comprising means attached to a moving frame for gripping contact with a stationary object, means for applying pressure to grip said first means upon excessive speed of said moving frame and means for relieving the pressure a slight amount upon stopping of the moving frame more abrupt than the predetermined maximum.

10 2. Apparatus of the character described comprising a pair of jaws attached to an elevator and traveling adjacent a stationary object, means operable upon excessive speed of said elevator to apply pressure forcing said jaws into engagement with said object to stop the elevator and means for relieving the pressure on said jaws when the stopping of the elevator exceeds the predetermined abruptness.

15 3. Apparatus of the character described comprising a pair of jaws attached to an elevator and traveling therewith adjacent to a stationary object, means for exerting pressure to lock said jaws to said object upon excessive speed of the elevator to stop the same and means interposed between one of said jaws and the pressure applying means causing release of said jaw upon excessively abrupt stopping of the elevator.

20 4. Apparatus of the character described comprising gripping jaws attached to an elevator for contact with a stationary object, a wedge member for operating said gripping jaws and inertia means co-operating with said jaws to stop said elevator within substantially the same distance of travel for all load conditions when said elevator exceeds predetermined maximum speed.

25 5. In a device of the character described, an elevator having safety jaws adapted to grip a safety rail, a wedge to force said jaws into engagement with said rail, and a weight connected to one of said jaws so that movement of the weight relative to the jaw changes the distance from the central axis of the wedge to the point of force application of said jaw.

30 6. In a device of the character described, an elevator having safety jaws adapted to grip a safety rail, a wedge to force said jaws into gripping contact with said rail, and a levered weight screw-connected to one of said jaws so that movement of the weight up or down relative to the jaw changes the distance from the central axis of the wedge to the first point of force application on said jaw.

35 7. In a device of the character described, an elevator having safety jaws adapted to

grip a safety rail, one of said safety jaws being constructed at one end in the form of a fork, a wedge to force said jaws into engagement with said rail, a threaded rod passing through one of said jaws and serving as a force application member for said jaw, and a weighted lever secured to said rod so that rotation of said lever will change the distance from the wedge axis to the point of force application on said jaw.

40 In testimony whereof, I have signed my name to this specification.
